UNITED STATES PATENT OFFICE

140,090

DESIGN FOR A CONTROL HANDLE UNIT

William J. Turnbull, Towson, Md., and James R. Ward, Stamford, Conn., assignors to The Glenn L. Martin Company, Baltimore, Md.

Application February 17, 1944, Serial No. 112,686

Term of patent 14 years

(Cl. D10—8)

To all whom it may concern:

Be it known that we, William J. Turnbull and James R. Ward, citizens of the United States and residents, respectively, of Towson, county of Baltimore, State of Maryland, whose post-office address is 607 Marwood Road, Towson, county of Baltimore, State of Maryland, and city of Stamford, county of Fairfield, State of Connecticut, whose post-office address is R. F. D. 2, Long Ridge, city of Stamford, county of Fairfield, State of Connecticut, have invented a new, original, and ornamental Design for a Control Handle Unit, of which the following is a specification, reference being had to the accompanying drawings, forming part thereof.

Figure 1 is a perspective view of a control handle unit showing our new design as it appears when in use, the broken lines being for illustrative purposes only.

Figures 2 and 3 are side elevations of one of the control handles, shown in Figure 1.

Figure 4 is a front elevational view thereof.

Figure 5 is a rear elevational view thereof.

We claim:

The ornamental design for a control handle unit, substantially as shown and described.

WILLIAM J. TURNBULL.
JAMES R. WARD.
